(57) **CLAIM**

We claim the ornamental design for a synthetic resin sheet, as shown and described.

DESCRIPTION

FIG. 1 is a synthetic resin sheet showing our new design; and, FIG. 2 shows the synthetic resin sheet of FIG. 1 in a position of use applied to a refrigerator.

The broken lines in the drawings represent environmental subject matter and portions of the synthetic resin sheet that form no part of the claim.

The thickness of the synthetic resin sheet forms no part of the claimed design.
